UNITED STATES PATENT OFFICE.

GEORGE H. WHEARY, OF RACINE, WISCONSIN, ASSIGNOR TO THE HARTMANN TRUNK COMPANY, OF RACINE, WISCONSIN, A CORPORATION OF WISCONSIN.

WARDROBE-TRUNK.

1,122,451.

Specification of Letters Patent. Patented Dec. 29, 1914.

Application filed January 24, 1912. Serial No. 673,028.

To all whom it may concern:

Be it known that I, GEORGE H. WHEARY, a citizen of the United States, and resident of Racine, in the county of Racine and State 5 of Wisconsin, have invented new and useful Improvements in Wardrobe-Trunks, of which the following is a description, reference being had to the accompanying drawings, which are a part of this specification.

10 This invention relates to improvements in wardrobe trunks of that type particularly adapted, although not solely, for use as a steamer trunk. Trunks of this type, when in use on a steamer, are placed beneath the 15 berth in the stateroom and it is a very desirable feature to provide a construction in which the cover may be opened and the wardrobe section swung to a vertical position of convenient accessibility without re-

20 moving the trunk from beneath the berth.

It is also a very desirable feature to provide a construction in which the wardrobe section may be entirely removed from the trunk and placed in upright position at any 25 convenient location.

It is one of the objects of this invention to provide a wardrobe trunk which is provided with the before mentioned desirable features and which is further provided with 30 means for firmly locking the wardrobe section in upright position so that it cannot be accidentally tipped over.

A further object of the invention is to provide a trunk of this type in which means 35 are provided for bracing the wardrobe section in upright position when removed and separated from the trunk.

A further object of the invention is to provide a compact wardrobe trunk which is 40 strong and durable, simple in construction and easily opened to positions of convenient accessibility.

With the above and other objects in view, the invention consists in certain novel features of construction and combination of parts, as set forth in the appended claims, and a preferred form of embodiment of 45 which is hereinafter specifically described with reference to the accompanying drawings which form part of the specification.

In the accompanying drawings in which

the same reference characters indicate the same parts in all of the views: Figure 1 is a front view of the improved wardrobe trunk, with both covers swung to open position and 55 the wardrobe section of the trunk drawn out and swung up to its vertical position and locked; Fig. 2 is a horizontal sectional view of a portion of the trunk taken on line 2-2 of Fig. 1; Fig. 3 is a sectional view of 60 the trunk taken on line 3-3 of Fig. 1; and Fig. 4 is a side view of a portion of the wardrobe section removed from the trunk and standing in vertical position with the bracing means also in position.

Referring to the drawing the numeral 8 indicates the body of the trunk which is of 65 a height to conveniently fit beneath a steamer berth, and 9 and 10 the front and upper covers respectively thereof.

The interior of the trunk is adapted to contain an upper tray 11 which is supported on the angle guide strips 12 and a unitary 70 wardrobe section 13 in the lower portion of the trunk and resting on the lower portion 75 of the trunk.

The wardrobe section of the trunk is open at the top and when the section is withdrawn from the trunk body and swung to upright position the open portion of the 80 section will face in the same direction as the end of the trunk body adjacent thereto. This section is adapted to contain the usual garment hangers and retainers 14 usually provided in a section of this character.

The front cover 9 is hinged to the lower edge of the trunk body and when in open position the upper face of the cover is approximately flush with the upper face of the lower wall of the trunk, and this cover face 90 near one end is provided with transversely extending rails 15 which are angular in cross section to offset the inner edges of the rails from the cover. The bottom portion (when within the trunk) of the wardrobe 95 section near one end is provided with a skid member 16 and at the other end with a hinged guide member 17. These two members support the wardrobe section a sufficient distance above the bottom portion of the 100 trunk and the cover (when in open position) to clear the offset rails when withdrawn

from the trunk body. The hinged member is provided with angular reinforcing edge strips 18 which are adapted to extend beneath the offset portions of the rails when 5 the wardrobe section is withdrawn from the trunk to serve as a guide for said section. The hinged member is connected to the wardrobe section by a pair of double jointed hinges 19 which permit the guide 10 member 17 to lie adjacent to and in a plane parallel with the bottom portion of the wardrobe section, when within the trunk, and to permit said section to be swung to a vertical position outside of the trunk with 15 the end of the section resting on the guide member, and in which position the lower section end will be in a plane parallel with relation to the said hinged guide member. In swinging the wardrobe section from a 20 horizontal to a vertical position the lower end corner of the said section will be swung in a direction toward the opposite end of the trunk to position the lower portion of the section directly in front of the opening 25 of the trunk body.

In order to securely lock and brace the wardrobe section in vertical position the forward edge of the upper portion of the trunk body is provided with a locking recess 30 20 which is of sufficient length to permit the side portion of said wardrobe section to be slid rearwardly therein when the said section is in vertical position, and when thus moved the said section will be braced and 35 locked against being swung to a horizontal position by the shoulders 21 formed by said recess.

The upper cover 10 of the trunk body is hinged comparatively a considerable distance 40 45 to the rear of the front recessed edge of the trunk in order to cover the recessed portion and also to reinforce this edge of the trunk when the trunk is in closed position. This upper cover is also provided with flanged reinforced front and side edges 22 which overlap and reinforce the edge portions of the front cover when in closed position.

If desired the wardrobe section may be 50 pulled out and away from the trunk body and swung to a vertical position and the hinged guide member swung rearwardly and at an angle, and its upper edge placed beneath the headed pins 23 projecting from 55 the said section, thus serving to brace the section in the manner shown in Fig. 4.

A handle 24 is provided on the upper end of the wardrobe section for convenience in swinging the section to an upright position.

60 The different portions of the trunk are provided with the usual reinforcing trimmings and other necessary parts.

In use, if it is desired to swing the wardrobe section to a vertical position it is only

necessary to pull the section out of the body 65 of the trunk and then take hold of the handle and swing the section upwardly to a vertical position, and in doing this the double jointed hinge will automatically move the lower end of the section toward 70 the opposite end of the trunk. When in vertical position a slight push inwardly on the section will cause it to slide into the locking recess and the section will be firmly locked and braced in position. If it is desired to 75 remove the wardrobe section entirely from the trunk body and stand it in another part of the room, this may be easily done and the guide member and the hinge will serve to brace the said section in position. 80

While the trunk has been described particularly as a steamer trunk it is to be understood that it is as well adapted for ordinary use in any manner desired.

From the foregoing description it will be 85 seen that the wardrobe trunk is well adapted for the purpose desired.

What I claim as my invention is:

1. A wardrobe trunk, comprising a body portion having a front opening and a cover 90 therefor hinged to swing downwardly, and a unitary wardrobe section positioned within the trunk body and adapted to be pulled horizontally outwardly therefrom and to engage the cover and to be tilted to a vertical position and to engage and be locked to the body portion while in vertical position. 95

2. A wardrobe trunk, comprising a body portion having a front opening and a cover 100 therefor hinged to swing downwardly to open position, said body portion provided with a wardrobe section engaging means, and a unitary wardrobe section positioned within the trunk body and adapted to be pulled horizontally outwardly therefrom 105 and to be tilted in front of the body portion to a vertical position and to be engaged by the wardrobe section engaging means.

3. A wardrobe trunk, comprising a body portion having a front opening and a cover 110 therefor hinged to swing downwardly, said body portion provided with a wardrobe engaging means, a unitary wardrobe section positioned within the trunk body, rails carried by the cover, and a guide member carried by the section, said wardrobe section adapted to be pulled horizontally out of the trunk body and to be tilted in front of the body portion to a vertical position and moved into engagement with the wardrobe 115 120 section of the trunk body, said guide member being moved into engagement with the rails by the outward movement of said wardrobe section.

4. A wardrobe trunk, comprising a body 125 portion having a front opening and a cover therefor hinged to swing downwardly, said body portion provided with a wardrobe sec-

tion engaging recess, rails carried by the cover, a wardrobe section positioned within the trunk body, and a guide member hinged to the wardrobe section and adapted to be drawn out with the wardrobe section and to slidably engage the rails, said wardrobe section when withdrawn from the trunk body and resting on the cover adapted to be swung on the guide member and to a vertical position and pushed into the wardrobe section engaging recess to lock said section in upright position.

5. A wardrobe trunk, comprising a body portion having a front opening and a cover therefor hinged to swing downwardly, said body portion provided with a wardrobe section engaging recess, rails carried by the cover, a wardrobe section positioned within the trunk body, and a guide member connected to the wardrobe section by a double jointed hinge and to be moved therewith, said wardrobe section adapted to be withdrawn from the trunk body and the guide member to engage the rails, said wardrobe section also adapted to be swung to a vertical position when withdrawn and to be pushed into the trunk body recess to lock said section in upright position.

6. A wardrobe trunk, comprising a body portion having a front opening and a recess in its upper edge, a cover hinged to the lower edge of said body portion and adapted to swing downwardly, rails carried by said cover and having offset portions, a wardrobe section positioned within the body portion, a guide member positioned between the wardrobe section and the bottom portion of the trunk, and double jointed hinges connecting the guide member to the wardrobe section, said guide member adapted to extend beneath the offset portions of the rails when said wardrobe section is pulled out from the trunk body and is resting on the cover and said double jointed hinges permitting the wardrobe section to be swung to a vertical position and laterally toward the opposite end of the trunk body, said wardrobe section also adapted to be pushed into the recess of the body portion to lock said recess in upright position.

7. A wardrobe trunk, comprising a body portion having a front opening and a recess in its upper edge, a cover hinged to the lower edge of said body portion and adapted to swing downwardly, rails carried by said cover and having offset portions, a wardrobe section positioned within the body portion, a guide member positioned between the wardrobe section and the bottom portion of the trunk, and double jointed hinges connecting the guide member to the wardrobe section, guide member engaging means provided in connection with the bottom portion of the wardrobe section which is

engaged by a portion of the guide member when the wardrobe section is removed from the trunk body and separated from the cover and the guide means is swung to a position to brace the said section, said guide member adapted to extend beneath the offset portions of the rails when said wardrobe section is pulled out from the trunk body and is resting on the cover and said double jointed hinges permitting the wardrobe section to be swung to a vertical position and laterally toward the opposite end of the trunk body, said wardrobe section also adapted to be pushed into the recess of the body portion to lock said recess in upright position.

8. A wardrobe trunk, comprising a body portion having a front opening and a recess in its upper edge, a cover hinged to the lower edge of said body portion and adapted to swing downwardly, another cover hinged to the upper portion of the trunk body and adapted to extend over the upper edge portion of the other cover and to cover the recess portion of the trunk body, rails carried by said cover and having offset portions, a wardrobe section positioned within the body portion, a guide member positioned between the wardrobe section and the bottom portion of the trunk, and double jointed hinges connecting the guide member to the wardrobe section, said guide member adapted to extend beneath the offset portions of the rails when said wardrobe section is pulled out from the trunk body and is resting on the cover and said double jointed hinges permitting the wardrobe section to be swung to a vertical position and laterally toward the opposite end of the trunk body, said wardrobe section also adapted to be pushed into the recess of the body portion to lock said recess in upright position.

9. A wardrobe trunk, comprising a body portion having a front opening and a cover therefor, and a unitary wardrobe section slidably positioned within the trunk body and arranged to be pulled horizontally outwardly to a position to clear the front of the trunk body and to be swung upwardly to a vertical position outside of the trunk body.

10. A wardrobe trunk, comprising a body portion having a front opening and a cover therefor, a unitary wardrobe section slidably positioned within the trunk body and arranged to be pulled horizontally outwardly to a position to clear the upper front edge of the trunk body and to be swung upwardly to a vertical position outside of the trunk body and while connected to the trunk, and means for holding the wardrobe section in vertical position.

11. A wardrobe trunk, comprising a body portion having a front opening and a cover

therefor, a unitary wardrobe section resting within the body in horizontal position, and a connecting mechanism for the wardrobe section, said mechanism being so constructed as to adapt the wardrobe section to be pulled horizontally outwardly from its normal horizontal position within the trunk, and to be swung upwardly to a vertical po-

sition outside of the trunk body and while held by the connecting mechanism. 10

In testimony whereof, I affix my signature, in presence of two witnesses.
